UNITED STATES PATENT OFFICE.

MATTHEW J. COSTELLO, OF NEW YORK, N. Y.

DESIGN FOR A SCARF, STOLE, OR MUFFLER.

Application filed April 4, 1923. Serial No. 5,694. Term of patent 7 years.

To all whom it may concern:

Be it known that I, MATTHEW J. COSTELLO, a citizen of the United States, residing in the city of New York, in the county and State of New York, have invented a new, original, and ornamental Design for a Scarf, Stole, or Muffler, of which the following is a specification, reference being had to the accompanying drawing, forming part thereof.

In the drawing, a scarf, is shown in perspective embodying the new ornamental design.

What I claim is:—

The ornamental design for a scarf, stole, or muffler, substantially as shown.

MATTHEW J. COSTELLO.
